UNITED STATES PATENT OFFICE

2,690,365

PISTON RING

Holly M. Olson, Muskegon, Mich., assignor to
Sealed Power Corporation, Muskegon, Mich., a
corporation of Michigan

Application August 11, 1951, Serial No. 241,447

3 Claims. (Cl. 309—45)

1

This invention relates to an improved replacement oil control piston ring, which is used under the more extreme worn conditions of cylinders, pistons and rings in internal combustion engines. Instead of reboring cylinders and using oversize pistons, and new and oversize rings, it is quite common practice in internal combustion engines that, when the engine becomes seriously defective, with considerable oil pumping and burning of such oil which causes objectional smoke and exhaust, the original piston rings are removed and replaced with rings of more drastic sealing qualities in order to control blow-by and oil pumping which takes place in the cylinders. When this occurs, the pistons have been worn undersize, while the cylinder bore is oversize, resulting in a loose fit of the pistons so that in their up and down reciprocating movements, the pistons may tilt with a slap action which disrupts and breaks the seal of conventional type oil control rings.

For a number of years piston rings, for conditions of the type noted, have usually been constructed of four parts all assembled in the oil groove of a piston. Such parts include a conventional corrugated spring expander at the bottom of the ring groove, with vent openings for passage of oil therethrough. Three other parts of the ring consist of upper and lower thin, substantially flat or slightly dished steel rails between which is a vented spacer holding the rails apart. The spacer has largely been made of cast iron and does not bear against the cylinder wall. The expander bears against the inner curved edges of the rails and presses them, at their outer curved edges, against the cylinder wall, supplying the main force of the pressure with which said rails engage the wall.

It is an object and purpose of the present invention to use for the spring expander and one thin steel rail, a unit made of thin steel which combines the functions of spacer and the other thin steel rail. By so doing, the number of ring parts in an oil ring for the purposes stated is reduced, each of the cylinder wall bearing rails may operate independently of the other, there is a greater ventilation through the combined rail and spacer for oil passage with avoidance of the danger of the vent openings being wholly or partly filled with carbon and the like, a better balanced unit pressure of the rail edges against the cylinder wall, and a simplification of manufacturing, stocking and packaging at the factory, and of the assembly of the ring parts in a piston ring groove.

2

An understanding of the invention may be had from the following description, taken in connection with the accompanying drawing, in which:

Fig. 1 is a fragmentary enlarged vertical section through a piston at the oil ring groove therein and associated cylinder, with a preferred structure of the piston ring of my invention located in the groove.

Fig. 2 is a fragmentary plan view of a blank of thin steel from which the preferred form of ring is made.

Fig. 3 is an edge view thereof.

Fig. 4 is an edge view of the completed unit of rail and spacer, which is used with an additional thin steel rail. It is the structure in Fig. 3 after final forming and shaping.

Fig. 5 is a plan view of the completed rail and spacer unit shown in Fig. 4.

Fig. 6 is a view, like that shown in Fig. 1, with a slight modification in the structure of the unit rail and spacer.

Figs. 7 and 8 are plan views of slightly modified blank forms from which the rail and spacer unit may be made, and

Fig. 9 is a fragmentary plan view of the rail and spacer unit made from the blank shown in Fig. 7.

Like reference characters refer to like parts in the different figures of the drawing.

The stock from which the spacer unit is made is of thin steel, usually approximately .020 to .025 inch in thickness. It is stamped to provide a rail section 1 and a parallel section at 2, by removing portions of the material, leaving the openings 3 separated by the transverse connectors 4. Each of the openings 3, at each end, at the section 1 is provided with recesses 5 as shown. In Fig. 8, the parallel section 2, substantially midway between the parts 4, has portions removed as at 6, leaving short sections 2a connected with the spaced connector portions 4.

In Fig. 2, instead of cutting part of the stock away to leave spaces at 6, the continuous section 2 is cut across midway between the parts 4 and end portions are turned at right angles to make struts 7.

The blanks of the type shown in Figs. 2, 7 and 8 are formed into a combined rail and spacer by bending the sections 2 or 2a generally at right angles to the connectors 4 at the outer ends of said connectors, and are again bent adjacent the bottoms of the recesses 5 to locate the rail portions 1 spaced from and substantially parallel to the sections 2 or 2a, and generally at

right angles to the connectors 4. It will be noted that the connectors 4 between the rail portion 1 or the sections 2 or 2a are located outwardly of the inner edges of the rail 1.

When my invention is used in a piston and placed in the groove thereof, such combined upper rail section and spacer is placed with two other members in the oil groove of a piston, as 8, which is to be installed in a cylinder 9. One of said other members is a conventional thin steel rail 10 located at the bottom of the groove. Such rail 10 from its outer to its inner edges is the same as the upper rail portion 1 of the combined steel rail and spacer unit, in the distance between outer and inner edges.

At the beginning of installation a corrugated spring expander 11 of conventional structure is located in the ring groove at the bottom thereof and the steel rail 10 and the combined rail and spacer of my invention are placed in the groove with the independent rail 10 at the bottom of the groove. With such installation, the expander 11 bears against the inner edges of the upper rail 1 and lower independent rail 10, forcing them with a substantially equal pressure against the wall of the cylinder 9. The struts 1 extending upwardly from the ends of the sections 2a, in Fig. 1, reach the upper rail 1 and support and hold it against fluttering or other undesired movement.

In Fig. 6 the structure is substantially the same as in Fig. 1, except that the unit, consisting of the upper rail 1 and the connected spacer is formed from a blank of the type shown in Fig. 7, there being no supporting struts 1. The continuous ring 2 rests upon the lower steel rail 10 the same as the sections 2a rest thereon in Fig. 1.

With the constructions shown which embody my invention, a less number of parts are required for the oil ring, each of the thin rails 1 and 10 are operable independent of each other to follow a cylinder wall, the oil ventilation through the openings made at 3 is large, there is a balanced unit pressure of the ring against the cylinder walls. The invention is particularly desirable in conjunction with the assembly of the parts therein in a piston ring groove, while in the factory there is a marked simplification in manufacturing, stocking and packaging.

The invention is defined in the appended

claims and is to be considered comprehensive of all forms of structure coming within their scope.

I claim:

1. A three part piston ring comprising, a lower, thin substantially horizontal metal rail, an upper like rail having spaced, downwardly extending connectors integral therewith positioned outwardly from the inner edges of said upper rail, located adjacent the inner edges thereof, each 10 connector at its lower end terminating in a horizontal section resting upon the lower rail, each of said horizontal sections, at each end thereof having an integral upwardly extending strut, the upper ends of the struts being substantially against the lower side of said upper rail, and a 15 spring member back of and bearing against the inner edges of said upper and lower rails.

2. A combined rail and spacer structure comprising, a generally flat, thin circular metal rail having, adjacent its inner edges, spaced, integral, downwardly extending connectors positioned outwardly from the inner edges of said upper rail, each at its lower end terminating in a generally flat, horizontal section, the said sections 20 at adjacent ends of successive sections being spaced apart, and the outer edges of said sections being set inwardly from the outer edges of said rail, each of said sections at each end having an integral upwardly extending strut, 25 the upper ends of the struts extending substantially to the under side of said rail.

3. A combined rail and spacer structure comprising, a generally flat, thin circular metal rail having, adjacent its inner edges, spaced, integral, 30 downwardly extending connectors, positioned outwardly from the inner edges of said upper rail, each at its lower end terminating in a generally flat horizontal section, the said sections at adjacent ends of successive sections being spaced apart, and each section having an integral upwardly extending strut, the upper ends of the struts extending substantially to the under side 35 of said rail.
